UNITED STATES PATENT OFFICE.

CHARLES VINCENT DAIGER, JR., OF NEWTON, MASSACHUSETTS.

DESIGN FOR A LAMP STAND.

Application filed August 5, 1927. Serial No. 23,005. Term of patent 3½ years.

To all whom it may concern:

Be it known that I, CHARLES VINCENT DAIGER, JR., a citizen of the United States, residing at Newton, in the county of Middlesex and State of Massachusetts, have invented a new, original, and ornamental Design for Lamp Stands, of which the following is a specification, reference being had to the accompanying drawing, forming a part thereof.

The figure is a perspective view of the lamp stand showing my new design.

I claim:

The ornamental design for a lamp stand as shown.

C. VINCENT DAIGER.
